UNITED STATES PATENT OFFICE.

WILLIAM H. INSLEY AND ALVIN C. RASMUSSEN, OF INDIANAPOLIS, INDIANA, ASSIGNEES TO INSLEY MANUFACTURING COMPANY, OF INDIANAPOLIS, INDIANA, A CORPORATION OF INDIANA.

CONCRETE CHUTING PLANT.

1,285,717.

Specification of Letters Patent. Patented Nov. 26, 1918.

Application filed April 14, 1917. Serial No. 162,044.

To all whom it may concern:

Be it known that we, WILLIAM H. INSLEY and ALVIN C. RASMUSSEN, citizens of the United States, residing at Indianapolis, in 5 the county of Marion and State of Indiana, have invented a new and useful Concrete Chuting Plant, of which the following is a specification.

The object of our invention is to provide, 10 in that type of concrete-handling devices which comprises an elevator, a vertically adjustable receiving hopper, and an adjustable gravity chute receiving material from said hopper, means by which the contents of the 15 elevator may be automatically dumped into the hopper in whatever position of vertical adjustment the hopper may be placed, said means being of such character that it may be manipulated so as to permit perfect free- 20 dom of vertical adjustment of the hopper upon the supporting tower.

The accompanying drawings illustrate our invention. Figure 1 is a side elevation of an apparatus embodying our invention; 25 Fig. 2 a perspective detail of a section of the tower, the elevator, the receiving hopper, and our attachment; Fig. 3 a fragmentary detail of the outer end of one of the switches; Fig. 4 an elevation of the switch mounting; 30 and Fig. 5 a plan.

In the drawings, 10 indicates a tower structure of any desired form provided with vertical ways 11 which form a guide for the elevator 12 which carries a dumping bucket 13 provided with rollers 14 at its forward upper corners. The bucket 13 is of that common type which is normally counterbalanced on the side of its axis 15 opposite rollers 14 so that the bucket itself, as well 35 as the loaded bucket, is in a normally stable condition on the elevator 12. Mounted so as to be vertically slideable upon tower 10 is a hopper carriage 21 which may be vertically lifted by means of a lifting cable 22 attached to its upper portion. On this vertically movable carriage 21 is secured a hopper 23 and in common practice the carriage 21 may also be extended to carry a boom seat 24 and a tackle block head 25. 40 Our invention resides in the provision of switches carried by hopper 23 in such manner that they may be readily manipulated to permit the convenient raising and lowering of hopper 23. We attach to the

frame 21 just above the hopper 23 a cross 55 bar 30 upon which are mounted a series of ears 31 arranged in two pairs. Each pair of ears 31 forms a support for a pivot pin 32 upon which is pivoted a switch 33 said switch comprising a pair of parallel curved 60 brackets 34 spaced apart a distance sufficient to permit the entry of a roller 14. The lower track 34 is extended at its front end and attached to its vertical flange is a finger 35 spaced a short distance from the 65 vertical flange of track 34 so as to form a crotch or notch 35' capable of receiving the lower end of a rod 36 carrying a nut or head 37 at its lower end. Each rod 36 has its upper end pivoted at 38 to frame 21 and is 70 preferably formed in two parts connected by a turn-buckle 39.

In operation, the switches 33, being pivoted upon pins 32, may be readily swung to the position occupied by the right hand 75 switch in Fig. 2, where the initial end of the switch is thrown upwardly and entirely outside the vertical plane of the front of the tower 21, so that the switches during the raising or lowering of hopper 23 will clear 80 the tower structure. Whenever the hopper has been brought to a desired position of vertical adjustment upon the tower, however, the switches may be thrown up so as to project their initial curved ends into the 85 tower space in position to receive the rollers 14. The lefthand switch in Fig. 1 is shown in the process of being thrown to active position, the operator slipping the rod 36 into the notch or crotch 35' with head 37 90 under finger 35 and the vertical flange of the track 33. Under normal conditions it is not necessary to tighten rod 36 in conjunction with the switches but this may be done by turn-buckle 39, if desired. When 95 it is desired to shift the hopper upon the tower, the operator has merely to slip rods 36 from crotches 35' and then swing the switches to inactive position during the shifting of the hopper.

We claim as our invention:

1. In an apparatus for handling slush concrete, the combination with a tower and dumping elevator bucket arranged therein, of a hopper vertically adjustable upon the tower, and a switch movably mounted upon the hopper and movable into active position relative to the dumping bucket and movable

out of said active position and beyond interference with the tower, and means for holding said switch in active position.

2. In an apparatus for handling slush concrete, a hopper carriage adapted to be mounted upon a vertical tower for vertical adjustment thereon, a hopper carried by said carriage, a switch pivoted upon said carriage and formed for coöperation with a dumping bucket to be mounted in the tower whereby said switch may be projected into active dumping position and withdrawn so as to clear the tower structure, and means for holding the switch in its active position.
- 10 3. In an apparatus for handling slush

concrete, a hopper carriage adapted to be mounted upon a vertical tower for vertical adjustment thereon, a hopper carried by said carriage, and a switch pivoted upon said carriage and formed for coöperation with a dumping bucket to be mounted in the tower whereby said switch may be projected into active dumping position and withdrawn so as to clear the tower structure.

In witness whereof we have hereunto set 25 our hands at Indianapolis, Indiana, this fourth day of April, A. D. one thousand nine hundred and seventeen.

WILLIAM H. INSLEY.
ALVIN C. RASMUSSEN.
